Inventor:

Nicholas W. Akimoff,

By Jas. C. Neumann
Attorney.

UNITED STATES PATENT OFFICE.

NICHOLAS W. AKIMOFF, OF WYNNEWOOD, PENNSYLVANIA.

SPRING.

Application filed October 5, 1920. Serial No. 414,730.

To all whom it may concern:

Be it known that I, NICHOLAS W. AKIMOFF, a citizen of the United States, residing at Wynnewood, in the county of Montgomery and State of Pennsylvania, have invented certain new and useful Improvements in Springs, of which the following is a specification.

My invention relates to springs, and it relates more particularly to a spring construction having means for adjusting the resiliency thereof.

The principal object of my invention is to provide a spring device of relatively simple and inexpensive construction which is so arranged that the resiliency of the spring proper may be readily and conveniently varied within practical limits for various purposes.

20 The nature and characteristic features of my invention will be more readily understood from the following description taken in connection with the accompanying drawings forming part hereof, in which

25 Figure 1 is an elevational view of a spring construction embodying the main features of my present invention, having means forming part thereof for varying its resiliency;

30 Fig. 2 is a vertical central section taken on the line 2—2 of Fig. 1; and

Fig. 3 is a horizontal section taken on the line 3—3 of Fig. 2.

Referring to the drawings, in the particular embodiment of my invention therein shown, 5 is a helical coil spring of usual type, one end of which may be squared as at 6 in the usual manner, but the other end of which is formed in the helical curve, the same as the main body portion of the spring. The end of the spring which follows the helical curve is mounted on a mandrel 7 made of a plurality of segments and having on its external surface a helical groove 8 complementary to the interior surface of the spring 5, in which groove the coils forming the end of the spring 5 are seated.

55 The mandrel 7 is provided at a portion above the helical groove 8 with a circumferential groove 9, in which a ring 10 is seated, which ring 10 serves as a kind of fulcrum or hinge to permit desired movement of the segments composing the mandrel 7 with respect to each other, as will later appear.

55 To further maintain the relative positions of the segments composing the mandrel 7,

there may be provided ball dowels 11, seated in complementary recesses 12, as shown in Figs. 2 and 3 of the drawings. The spaces 26 between the segments composing the 60 mandrel 7 diverge upward and downward from the point adjacent the hinge groove 9, so as to permit the requisite hinge-like motion of the segments composing the mandrel, as clearly shown in Fig. 1 of the drawings. 65

The lower interior of the mandrel 7 is tapered as at 13, and in this tapered portion, there is positioned a tapered plug 14, which is mounted on a spindle 15, carried at the lower end of a rotatable member 16. The 70 member 16 is provided with a threaded portion 17, which engages a complementary threaded portion 18 of the interior of the mandrel 7. The member 16 has a frustoconical portion 19 above the threaded portion 17, the surface of which is engaged by overhanging lips 20 of the segments composing the mandrel 7. Above the frustoconical portion 19 of the member 16 there is provided a disc portion 21, which serves as 80 a seat for the upper end of the spring construction, and there may also be provided a central recess 22, which will serve, when desired, to position the upper end of the spring construction by means of a suitable seat, 85 not shown, on the structure in connection with which the spring is used. The lower end of the spindle 15 upon which the tapered plug 14 is mounted may be provided with a head portion 23, which will insure 90 the retraction of the tapered plug 14 when the member 16 is unscrewed with respect to the mandrel 7, or if desired the tapered plug 14 may be made integral with the member 16.

The manner of effecting the adjustment of 95 the resiliency of the spring may now be explained. By unscrewing the member 16 with respect to the mandrel 7, the tapered plug 14 will be retracted in the interior of the segmental mandrel 7, thus permitting the 100 lower end thereof, which is engaged by the coils of one end of the spring 5, to be rotated with respect to the spring, retracting or advancing the same a sufficient distance to release a greater or less extent of the coils 105 of the spring, after which the member 16 may be screwed into the segmental mandrel 7, causing the tapered plug 14 to advance and spread the lower portion of the mandrel 7 sufficiently to tightly grip the coils which 110 are seated in the groove 8.

To assist in the manipulation, the upper

portion of the mandrel 7 may be provided with holes or recesses 24, adapted to be engaged by a suitable spanner wrench, and likewise the seat portion 21 of the member 16 may be provided with suitable recesses 25, for the same purpose.

It will be noted that as the member 16 is unscrewed and thereby retracted within the mandrel 7, the frusto-conical portion 19 thereof will engage the over hanging lips 20, and thereby insure the contraction of the lower portion of the mandrel 7, and thus release the grip on the coils of the spring which are seated in the groove 8, to permit 15 the adjustment thereof in said groove, as hereinbefore described. It will, of course, be understood that the interior threads 18 which are engaged by the threaded portion 17 of member 16 will be of such dimension 20 and shape as to permit the relative hinge movement of the segments comprising the mandrel 7.

Having thus described the nature and characteristic features of my invention, 25 what I claim as new and desire to secure by Letters Patent, is:

1. A spring device comprising a coil spring, and a mandrel upon which one end of said coil spring is mounted having a helical groove complementary to the interior surface of said coil spring, said mandrel comprising a plurality of segmental sections expandable relatively to each other to thereby securely clamp said spring to 35 said mandrel in adjusted positions.

2. A spring device comprising a coil spring, a mandrel upon which one end of said coil spring is mounted having a helical groove complementary to the interior surface 40 of said coil spring, said mandrel comprising a plurality of segmental sections expandable relatively to each other, and an expanding device mounted in said mandrel, the arrangement being such that said spring 45 may be securely clamped to said mandrel in adjusted positions.

3. A spring device comprising a coil spring, a mandrel upon which one end of said coil spring is mounted having a helical groove complementary to the interior surface 50 of said coil spring, said mandrel comprising a plurality of segmental sections hinged relatively to each other, and an expanding device mounted in said mandrel, the arrangement being such that said spring 55 may be securely clamped to said mandrel in adjusted positions.

4. A spring device comprising a coil spring, a mandrel upon which one end of 60 said coil spring is mounted having a helical groove complementary to the interior surface of said coil spring, said mandrel comprising a plurality of segmental sections 65 hinged relative to each other, and an expanding device mounted in said mandrel.

comprising a tapered plug engaging a complementary interior portion of said mandrel, the arrangement being such that said spring may be securely clamped to said mandrel in adjusted positions.

5. A spring device comprising a coil spring, a mandrel upon which one end of 70 said coil spring is mounted having a helical groove complementary to the interior surface of said coil spring, said mandrel comprising a plurality of segmental sections hinged relatively to each other, an expanding device mounted in said mandrel comprising a tapered plug engaging a complementary interior portion of said mandrel, and means 75 for advancing and retracting said tapered plug within said mandrel whereby said spring may be securely clamped to said mandrel in adjusted positions.

6. A spring device comprising a coil 80 spring, a mandrel upon which one end of said coil spring is mounted having a helical groove complementary to the interior surface of said coil spring, said mandrel comprising a plurality of segmental sections hinged 85 relatively to each other, an expanding device mounted in said mandrel comprising a tapered plug engaging a complementary interior portion of said mandrel, and means for advancing and retracting said tapered 90 plug within said mandrel comprising a spindle in threaded engagement with said mandrel.

7. A spring device comprising a coil 95 spring, a mandrel upon which one end of said coil spring is mounted having a helical groove complementary to the interior surface of said coil spring, said mandrel comprising a plurality of segmental sections hinged 100 relatively to each other, an expanding device mounted in said mandrel comprising a tapered plug engaging a complementary interior portion of said mandrel, means for advancing and retracting said tapered plug within said mandrel, and means for insuring 105 the contraction of said mandrel when said tapered plug is retracted.

8. A spring device comprising a coil 110 spring, a mandrel upon which one end of said coil spring is mounted having a helical groove complementary to the interior surface 115 of said coil spring, said mandrel comprising a plurality of segmental sections hinged relatively to each other, an expanding device mounted in said mandrel comprising a tapered plug engaging a complementary interior portion of said mandrel, means for advancing and retracting said tapered plug within said mandrel comprising a spindle in threaded engagement with said mandrel, 120 and means for insuring the contraction of said mandrel when said tapered plug is retracted.

9. A spring device comprising a coil 125 spring, a mandrel upon which one end of 130

said coil spring is mounted having a helical groove complementary to the interior surface of said coil spring, said mandrel comprising a plurality of segmental sections hinged 5 relatively to each other, an expanding device mounted in said mandrel comprising a tapered plug engaging a complementary interior portion of said mandrel, means for advancing and retracting said tapered plug 10 within said mandrel comprising a spindle in threaded engagement with said mandrel, and means for insuring the contraction of said mandrel when said tapered plug is retracted comprising a frusto-conical portion 15 of said threaded spindle and complementary portions of the mandrel adapted to be engaged by said frusto-conical portion.

10. A spring device comprising a coil spring, a mandrel upon which one end of 20 said coil spring is mounted, said mandrel comprising a plurality of segmental sections hinged relatively to each other, and an expanding device mounted in said mandrel comprising a tapered plug engaging a complementary interior portion of said mandrel, whereby said spring may be securely 25 clamped to said mandrel in adjusted positions.

11. A spring device comprising a coil 30 spring, a mandrel upon which one end of

said coil spring is mounted, said mandrel comprising a plurality of segmental sections hinged relatively to each other, and an expanding device mounted in said mandrel, whereby said spring may be securely clamped 35 to said mandrel in adjusted positions.

12. A spring device comprising a coil spring, a mandrel upon which one end of 40 said coil spring is mounted, said mandrel comprising a plurality of segmental sections hinged relatively to each other, and an expanding device mounted in said mandrel, the hinge connecting said segmental sections comprising a ring member mounted in a circumstantial groove in said mandrel. 45

13. A spring device comprising a coil spring, a mandrel upon which one end of said coil spring is mounted, said mandrel comprising a plurality of segmental sections hinged relatively to each other, and an expanding device mounted in said mandrel, the hinge connecting said segmental sections comprising a ring member mounted in a circumferential groove in said mandrel, and dowels 50 mounted in recesses in adjacent surfaces of 55 said segmental sections.

In testimony whereof, I have hereunto signed my name.

NICHOLAS W. AKIMOFF.
